UNITED STATES PATENT OFFICE.

NATHANIEL C. HALL, OF OLD LYME, CONNECTICUT.

STRAWBERRY HULLER.

1,416,818.

Specification of Letters Patent. Patented May 23, 1922.

Application filed March 22, 1922. Serial No. 545,759.

To all whom it may concern:

Be it known that I, NATHANIEL C. HALL, a citizen of the United States, residing at Old Lyme, in the county of New London and State of Connecticut, have invented a new and useful Improvement in Strawberry Hullers; and I do hereby declare the following, when taken in connection with the accompanying drawings and the characters of reference marked thereon, to be a full, clear, and exact description of the same, and which said drawings constitute part of this application, and represent, in—

Fig. 1, a face view, partly in section, of a strawberry huller constructed in accordance with my invention.

Fig. 2, a side view of the same.

Fig. 3, a face view, partly in section, illustrating a modified form of my invention.

Fig. 4, a side view of the same.

Fig. 5, a broken perspective view, showing the notched end of one of the jaws.

This invention relates to improvements in strawberry hullers, and particularly to the type which consists of two jaws adapted to be pressed together. In the more general construction of strawberry hullers, considerable pressure is required to bring the gripping edges of the jaws together, and, furthermore, they are sometimes liable to become out of line, so as not to properly grip the hull. The object of this invention is to provide the gripping members with a bearing at their inner edges, whereby the gripping edges will meet, and a light spring may be employed so as to require but little pressure, and the invention consists in the construction as will be hereinafter described and particularly recited in the claims.

In carrying out my invention, I employ two gripping-jaws 5 and 6, preferably struck up from sheet-metal and longitudinally and transversely bowed. These jaws are secured to the ends of a loop-like spring-handle 7, and preferably the gripping-members will be formed with integral projections

8, extending through slots 9 formed in the springs over which the ends of the projections are upset, so as to firmly rivet the jaws to the spring. Preferably, these jaws have 50 rearwardly-extending arms 10, which are notched near their ends, so as to be interlocked, and whereby a bearing is formed for the inner edges of the jaws, and whereby, also, the jaws are kept in alignment, so 55 that their outer ends will meet. Instead of forming the jaws with arms 10, as described, they may be in the form of cups 11, as shown in Fig. 3 of the drawings, riveted or otherwise secured to the ends 12 of a handle 13, 60 and extending from the handle to a point between the inner edges of the jaws is a plate 14, this plate and the two members of the handle being firmly secured together by rivets 15, so that the jaws will be held in 65 proper relation to each other, and by providing a bearing for the inner edges of the jaws, a light spring may be employed.

I claim:

1. A strawberry huller comprising a pair 70 of jaws connected with a spring-handle, and a bearing for the inner ends of said jaws.

2. A strawberry huller comprising a pair of jaws, a spring-handle, to the ends of which the jaws are respectively secured, said 75 jaws formed with rearwardly-extending arms which meet to form a bearing.

3. A strawberry huller comprising a pair of jaws, a spring handle, to the ends of which the jaws are respectively secured, said 80 jaws formed with rearwardly-extending arms provided near their inner ends with notches, whereby they are interlocked one with another.

In testimony whereof, I have signed this 85 specification in the presence of two subscribing witnesses.

NATHANIEL C. HALL.

Witnesses:

GORDON L. HALL,
MAY S. JORDAN.
